(57) **CLAIM**

The ornamental design for a stand mixer, substantially as shown.

DESCRIPTION

FIG. 1 is a side elevation view from one side of the stand mixer of the present invention.

FIG. 2 is a side elevation view from the opposite side.

FIG. 3 is a front top perspective view of the stand mixer.

FIG. 4 is a rear perspective view of the stand mixer.

FIG. 5 is a front elevation view of the stand mixer.

FIG. 6 is a rear elevation view of the stand mixer.

FIG. 7 is a top plan view of the stand mixer; and,

FIG. 8 is a bottom plan view of the stand mixer.

The features shown in broken lines form no part of the claimed invention.
